UNITED STATES PATENT OFFICE

123,927

DESIGN FOR A COMBINED ASH TRAY AND CIGARETTE SNUFFER

Bernard Thal, Boston, Mass., assignor to Robert
I. Bradley, Belmont, Mass., doing business as Precision Products Company, Waltham, Mass.

Application August 10, 1940, Serial No. 94,353

Term of patent 7 years

To all whom it may concern:

Be it known that I, Bernard Thal, a citizen of the United States, residing in Allston District of the city of Boston, county of Suffolk, and State of Massachusetts, have invented a new, original, and ornamental Design for a Combined Ash Tray and Cigarette Snuffer, of which the following is a specification, reference being had to the accompanying drawing, forming part thereof, wherein:

Fig. 1 is a plan view of the combined ash tray and cigarette snuffer, showing my new design; and

Fig. 2 is a side elevation of the same.

I claim:

The ornamental design for a combined ash tray and cigarette snuffer, substantially as shown.

BERNARD THAL.
